UNITED STATES PATENT OFFICE.

ARLIE H. GOODMAN, OF PITTSBURGH, PENNSYLVANIA, ASSIGNOR TO BLAW-KNOX COMPANY, OF PITTSBURGH, PENNSYLVANIA, A CORPORATION OF PENNSYLVANIA.

PORt CONSTRUCTION FOR FURNACES.

1,388,559.

Specification of Letters Patent. Patented Aug. 23, 1921.

Application filed November 10, 1919. Serial No. 336,939.

To all whom it may concern:

Be it known that I, ARLIE H. GOODMAN, a citizen of the United States, residing at Pittsburgh, in the county of Allegheny and State 5 of Pennsylvania, have invented a new and useful Improvement in Port Constructions for Furnaces, of which the following is a full, clear, and exact description, reference being had to the accompanying drawings, 10 forming part of this specification, in which—

Figure 1 is a transverse vertical section of a portion of a glass tank furnace embodying my invention.

Fig. 2 is a side elevation of the portion of 15 the furnace embodying the invention.

Fig. 3 is a partial horizontal section, and

Fig. 4 is a vertical section on the line 20 IV—IV of Fig. 2.

My invention has relation to port construction for furnaces and relates more particularly to means of novel character for facilitating the insertion and removal of the port coolers of the furnace.

25 My invention is designed to provide a construction by which the coolers employed at the inner or nose ends of the partition wall between the gas and air ports of the furnace may be more readily inserted and 30 removed.

In the accompanying drawings I have illustrated my invention as applied to a glass tank furnace, but it will be readily understood that it may be used in connection with 35 other furnaces having similar gas and air port construction.

In the accompanying drawings the numeral 2 designates a portion of the body of a glass tank furnace. 3 designates the air 40 port, 4 the air uptake, 5 the gas port and 6 the gas uptake. 7 is a horizontally extending partition wall which separates the air and gas ports in the usual manner.

It is customary in furnaces of this character to employ a cooler at the inner or nose 45 end of the wall 7. The particular form of cooler which I have illustrated and which is shown at 8, consists of a hollow metal box having suitable connections 9 for circulating water or other cooling fluid therethrough. This box is seated against the inner end of the wall 7 and is supported, as best shown in Fig. 4, in the side walls 10 50 of the port structure.

55 In order to facilitate the insertion and

removal of these boxes so that they may be readily renewed, or removed for repairs and replaced, I provide each of the port side walls 10 with a removable portion 10^a whose lower edges seat directly upon the inner portions of the cooler and which extend upwardly to the roof wall 11. I also provide this roof wall with a removable transverse section 12 which rests upon the upper end of the removable side portions 10^a. 60 65

It will be readily seen that the portions 10^a and 12 may be readily removed and that, when so removed, the cooler 8 can be quickly taken out and replaced. This makes the renewal or repair of the port coolers a relatively simple operation which can be carried out in a short time and with very little delay in the operation of the furnace. The removable side portions 10^a are preferably somewhat wedge-shaped in cross section, as 70 shown in Fig. 3, and may be provided with shoulders 10^b in order to make a better seating in the side walls 10. 75

I claim:

1. The combination with a furnace having 80 an air port, a gas port, and a refractory wall between said ports, of a hollow water cooled member extending transversely across the furnace and forming an inward continuation or extension of said wall, said member 85 being seated at its ends in the side walls of the furnace structure, and said side walls, together with the furnace roof, above said member, each having a section which can be bodily removed to permit of removal and replacement of said member, substantially as described. 90

2. The combination with a furnace having 95 an air port, a gas port, and a refractory wall between said ports, of a hollow water cooled member extending transversely across the furnace and forming an inward continuation or extension of said wall, said member being seated at its ends in the side walls of the furnace structure, and said side walls, together with the furnace roof, above said member, each having a section which can be bodily removed to permit of removal and replacement of said member, said member having its upper, lower, and inner end surfaces directly exposed to the surrounding port spaces, substantially as described. 100 105

In testimony whereof, I have hereunto set my hand.

ARLIE H. GOODMAN.
